UNITED STATES PATENT OFFICE

148,949

DESIGN FOR A SEWING MACHINE CABINET

Wilbur J. Peets, Elizabeth, N. J., assignor to The
Singer Manufacturing Company, Elizabeth,
N. J., a corporation of New Jersey

Application March 23, 1946, Serial No. 127,827

Term of patent 14 years

(CL. D33—12)

To all whom it may concern:

Be it known that I, Wilbur J. Peets, a citizen of the United States, residing at Elizabeth, in the county of Union and State of New Jersey, have invented a new, original, and ornamental Design for a Sewing Machine Cabinet, of which the following is a specification, reference being had to the accompanying drawings, forming a part thereof.

Fig. 1 is a perspective view of a cabinet in closed condition showing my new design.

Fig. 2 is a perspective view of the cabinet in its opened condition.

I claim:

The ornamental design for a sewing machine cabinet, as shown and described.

WILBUR J. PEETS.
